UNITED STATES PATENT OFFICE.

ALBERT W. PAUL, OF CHICAGO JUNCTION, OHIO.

SHADE-ROLLER.

1,258,940.

Specification of Letters Patent. Patented Mar. 12, 1918.

Application filed November 16, 1915. Serial No. 61,829.

To all whom it may concern:

Be it known that I, ALBERT W. PAUL, a citizen of the United States, residing at Chicago Junction, in the county of Huron and State of Ohio, have invented certain new and useful Improvements in Shade-Rollers, of which the following is a specification.

My present invention relates to a new and improved shade roller; and the primary object thereof is to provide a device of this character that affords facilities for fixing the upper end of the shade thereto and provides for the accommodation of shades of various widths.

Another object of this invention is to provide an improved shade roller that may be constructed entirely of metal parts which will of course insure its longevity yet not materially add to its weight or the cost of manufacturing.

A further object is to provide a shade roller which includes means for preventing binding of the coil actuating spring thus providing for the complete operativeness of the device at all times and guarding against breakage of the spring.

A still further object of the invention is to provide a device of the type in question that is extremely simple in construction and which, it is believed may be manufactured at a minimum cost.

Various other objects and advantages will become apparent during the continuance of the following description.

The above and other objects which will become apparent, are accomplished by such means as are shown in their preferred form in the accompanying drawings, described in the following specification and then more specifically pointed out in the appended claim.

In the accompanying drawings wherein like characters designate like parts throughout the several views;

Figure 1 is a view in side elevation showing my invention in its preferred embodiment; the shade being shown broken away.

Fig. 2 is a view in longitudinal section.

Fig. 3 is a fragmentary view showing in detail certain means for retaining the shade in place.

Fig. 4 is a view in section taken on line 4—4 of Fig. 3.

Fig. 5 is a view in section taken on line 5—5 of Fig. 2. 55

Fig. 6 is a view in section taken on line 6—6 of Fig. 2.

Fig. 7 is a perspective view of a detail.

Fig. 8 is a similar view.

Fig. 9 is a fragmentary view of additional means for securing the shade in place. 60

In the drawings the numeral 10 designates the body portion of my improved shade roller which, in the present embodiment, is shown in the form of a tubular member constructed of sheet metal. At one end the body 10 is formed into an annular offset portion 11. In practice a cap 15 is arranged at one end of the body 10 and has an inturned flange 16 for engagement with the offset portion 11. A disk 17 is carried within the cap 15 and is provided with a central opening 18 and a pair preferably diametrically opposite pawl seats 19. When the pawl-seats assume this position a pair of pawls 70 20 may be mounted therein as shown in Fig. 2. Beyond the disk 17 a bearing 21 is mounted in the cap 15 while the outer marginal edge of the latter is bent inwardly as at 22 to hold the parts in their relative positions. 80

The body 10 is slotted intermediate its ends as at 23 so as to receive tongues 24 on the bearing 25. The tongues 24 are preferably bent into the position shown in Fig. 2 so that their outer edges lie flush with the periphery of the body. In order to engage a coil spring, such as will presently be described, the bearing 25 is further provided with a pair of substantially parallel tongues 26. 90

A shaft 27 is now provided, one end thereof projecting through the coincident opening in the disk 17 and being flattened as at 28 for engagement with a suitable bracket (not shown) on the window frame. The other end of the shaft is loose with respect to the bearing 25 yet may be supported in connection therewith as will be presently pointed out. A coil spring 29 has one end fixed to the shaft 27 as at 30 while its other end 31 has connection with the bearing 25. In view of the fact that the tongues 26 bear against the adjacent portion of the coil spring, tightening of the latter upon the shaft 27 is prevented and at the same time 100 105 a bearing for the shaft 27 is provided. It

has been found that by adapting this structure in preference to journaling the inner end of the shaft 27 in the bearing 25, not only saves much time and labor in the manufacture of the device but also serves, efficiently, the function performed.

The shaft 27 is further provided with a ratchet 32 which is engaged by the pawls 20 as shown in Figs. 2 and 6. As the pawls 10 20 are slideable within their respective seats it will be understood that one of the pawls will always move by gravity into engagement with the ratchet irrespective of the position of the roller when the latter is rotated and stopped gradually.

In order to attach the end of the shade 33 thereto the body 10 is provided with a plurality of stamped ears 34 which engage the said shade in the manner clearly shown 20 in Figs. 1, 3 and 4. While this form of securing means has proven very advantageous I find it advisable to employ a second roller 35 that is split longitudinally as at 36 so as to be positioned about the body 25 10 and the shade 33 in the manner shown in Fig. 1. This second roller constitutes an auxiliary clamp for substituting the clamps or ears 34 at one end of the shade roller, and when this second roller or clamping 30 sleeve is employed, the unused clamping ears 35 may be pressed into the respective apertures from which they were struck up, thus avoiding obstruction to the clamping sleeve 35. After the second roller has been positioned 35 into place all liability of the shade becoming disengaged from the body 10 is eliminated.

At its outer end the second roller 35 carries a cap 37, which, in turn carries a trunnion 38. The trunnion 38, in the use 40 45 of my device is received within a suitable bracket (not shown) on the window frame. Thus it will be understood that by drawing the roller 35 outwardly the length of the device will be extended so as to accommodate shades of different widths or be used

in connection with window frames whereon the brackets are spaced a greater distance apart.

From the foregoing it is believed that the advantages and novel features of my invention will be readily understood and, therefore, further detailed description is deemed unnecessary.

In reducing my invention to practice I find that the form referred to herein as the 55 most practical and preferred embodiment is the most efficient, but realizing that certain conditions will necessarily vary in concurrence with the adoption of my device, I desire to emphasize the fact that various minor 60 changes in the details of construction and in the proportion of parts may be resorted to when required without sacrificing any of the advantages of my invention as defined in the appended claim.

Having thus fully described my invention, what I claim as new and desire to secure by Letters Patent is:

In a shade roller, a tubular body having 70 tongues extending inwardly, a member fixedly seated in said body by its engagement with the tongues of said body, said member having parallel elements extending toward one end of said body, a helical spring having one end fixedly engaged with said member and coiled around said parallel elements, and a shaft extending through said spring and through said end of the tubular body and having the other end of said spring secured thereto, whereby one end of said shaft is held against said member between said parallel elements, and whereby said cylindrical body may be rotated with relation to said shaft.

In testimony whereof I affix my signature 85 in presence of two witnesses.

ALBERT W. PAUL.
